(57) **CLAIM**

The ornamental design for a box kite strut connector, as shown and described.

DESCRIPTION

FIG. 1 is a top perspective view showing my new design; FIG. 2 is a bottom perspective view thereof;

FIG. 3 is a front view thereof;

FIG. 4 is a rear view thereof;

FIG. 5 is a left plan view thereof; and,

FIG. 6 is a right plan view thereof.

The broken lines in the drawings depict portions of the box kite strut connector that form no part of the claimed design.
